UNITED STATES PATENT OFFICE.

LOUIS FRIEDBERG, OF PHILADELPHIA, PENNSYLVANIA.

CIGARETTE-MAKER.

1,307,003.

Specification of Letters Patent. Patented June 17, 1919.

Application filed October 26, 1915. Serial No. 57,973.

To all whom it may concern:

Be it known that I, LOUIS FRIEDBERG, a citizen of the United States, residing at Philadelphia, in the county of Philadelphia and State of Pennsylvania, have invented new and useful Improvements in Cigarette-Makers, of which the following is a specification.

The invention relates to tobacco, and more particularly to implements for cigarette making, and has for an object to provide a device for quickly and efficiently making cigarettes.

Among other features the invention comprehends a device that can be readily carried in the pocket and which is conveniently adapted to filling cartridges or tubes of paper or the like, with tobacco, the entire operation being expeditiously accomplished without any loss of the tobacco and without tearing or breaking the tube or cartridge.

In the further disclosure of the invention reference is to be had to the accompanying drawings, constituting a part of this specification, in which similar characters of reference denote corresponding parts in all the views, and in which:

Figure 1 is a perspective view of the body or trough, showing the same filled with tobacco and a tube or cartridge, in dotted lines, in position to be filled,

Fig. 2 is a vertical longitudinal sectional view showing the pusher and guide, pressing the tobacco into the tube or cartridge, the cover or top being also shown,

Fig. 3 is a vertical transverse sectional view taken on the line 3—3 in Fig. 2,

Fig. 4 is a perspective view of the pusher and guide, the dotted lines indicating the folded position of the latter,

Fig. 5 is a vertical longitudinal sectional view of a slightly modified form of my invention, and

Fig. 6 is a vertical transverse sectional view of the structure shown in Fig. 5 and taken on the line 6—6 of the latter.

Referring more particularly to the views, I disclose a body or trough 10, substantially channel shaped and formed at one end with a tubular pointed holder 11 for a tube or cartridge 12, the holder 11 at its inner end being open to the trough 10. A pusher and guide 13 is provided and consists more particularly of a handled rod 14 and stem 15, curved in cross-section, with the stem extended beyond one end of the rod when in

use and preferably pointed on its free end, said stem, however, being hinged at 15^a so that it can be swung backward to lie upon the rod 14 when not in use.

60

A top or cover 16 is adapted to lie upon the trough 10 and press down the tobacco therein, said top having a transversely curved underface 17 and formed with guide-ways 18 lying upon the edges of the trough. 65

In the use of the device the tube or cartridge, 12 of paper or the like is placed upon the holder 11 with the holder extending into an end of the tube. The loose tobacco is now arranged in the trough 10 and the stem 70 15 is placed in the trough to lie upon the tobacco. The top or cover is now arranged in position and pressure is then exerted against the handle end of the pusher, thus advancing the stem into the tube 12 and 75 moving the inner end 19 of the rod into the trough to push the tobacco forwardly into the tube. The handle of the pusher is indicated by the numeral 20 and limits the inward movement of the pusher by abutting 80 against the trough 10. It will be clearly seen that the stem, acting as a guide will help to shape and form the tobacco so that it can enter the tube 12 through the holder 11 and also guide the tobacco into the tube. 85 The tube now filled with tobacco, is removed from the holder and is ready to be smoked, the same being a complete cigarette.

With the device of the character described the tobacco will be uniformly advanced into 90 the tube and will not "bunch up" therein, and furthermore by providing the stem 15 forming the guide, the tube will be held stiff and prevented from tearing as the tobacco advances into the latter.

95

In Figs. 5 and 6 I disclose a slightly modified form of my device, and in which the trough indicated by the numeral 10^a, has its cover or top 16^a and the pusher and guide 13^a made in one unit, as will be clearly perceived. The operation of the modified form is substantially the same as the operation of the preferred form, the cover or top 16^a in the former, however, being advanced along and in the trough 10^a with the pusher 100 105 and guide.

Having described my invention, I claim:

A cigarette maker comprising a body grooved to provide a recess having an arcuate bottom and straight sides, said member 110 being adapted to receive and retain tobacco when in a horizontal position with the open

side of the recess uppermost, a cover coextensive with said body, a projecting rib on said cover adapted to be disposed between the straight sides of said recess and having 5 its lower edge concaved to coact with the arcuate bottom of the recess to form a substantially cylindrical bore, the sides of the cover laterally of said rib engaging the top edges of said body for limiting the projec-

tion of said rib thereinto, a tubular shell 10 supporting member secured upon one end of said body coaxially with the bore therein, and a pusher disposed within said bore and movable to discharge tobacco compressed within said bore through said tubular member into a shell supported thereon. 15

In testimony whereof I affix my signature.

L. FRIEDBERG.
